ROTOR ARM AND ELECTRICAL SYSTEM

Kenneth A. Graham, Birmingham, Mich., assignor to Chrysler Corporation, Highland Park, Mich., a corporation of Delaware

Continuation of application Ser. No. 796,530, Mar. 2, 1959. This application May 2, 1960, Ser. No. 26,373

4 Claims. (Cl. 315—219)

The present invention relates to internal combustion engines and has particular reference to a new and improved ignition system therefor.

The present invention is an improvement over the ignition system of Patent No. 2,819,428 and reference is also made to copending application of Omer E. Bowlus and Kenneth A. Graham, Serial No. 696,845, now Patent No. 2,984,760, filed November 15, 1957, relating to a surface gap spark plug which is described herein. This invention also relates to improvements over the ignition system of copending application Serial No. 796,448, filed March 2, 1959, of Omer E. Bowlus and Kenneth A. Graham, now abandoned.

This application is a continuation of my application Serial No. 796,530, now abandoned, entitled Rotor Arm and Electrical System, filed March 2, 1959.

In the conventional ignition coil and magneto energized ignition systems for internal combustion engines wherein spark plugs are used having air gaps of a width within the range of 0.020 to 0.035 inch, the voltages necessary to electrically break down the air dielectric within these plug gaps fall within the range of 4 to 25 thousand volts. The high voltage spark is followed by a low current arc of relatively long duration which is effective in igniting cold and/or lean fuel mixtures but does not impinge upon carbon and lead fouling deposits which partially short the electrodes of these air gap plugs, nor contain the concentrated energy required to raise the temperature of the spark to a degree sufficient to burn away these deposits on the insulator surface should the spark actually contact these deposits by internal flash over.

The lack of concentrated energy in the spark is due in part to the characteristics of the ignition coil and magneto energy sources which are characteristically slow in releasing their electrical energy. Their slow release of energy is particularly disadvantageous to ignition when sufficient plug fouling exists to drain or shunt to ground a relatively large portion of the total energy supplied to the plug. Should fouling deposits of any substantial conductive capacity develop on the plugs the total energy dissipated by the shunting effect thereof may be sufficient to prevent the voltage from building up high enough to initiate a spark in the plug gaps.

Moreover, when using a conventional air gap plug of the type shown for example in Patent No. 2,269,067 with these ignition coil or magneto energizing systems, the spark plug actually has little opportunity to burn away its own fouling deposits since the spark does not occur in the immediate vicinity of these deposits which form on the insulator surface between the base of the center electrode and the metal shell or ground electrode of the plug. When these energizing systems on the other hand are used with surface gap plugs where a spark can be effective in burning away fouling deposits, the rate of release of energy to the plugs is not sufficient to burn away the fouling deposits and also perform its fuel ignition function.

A major object of this invention, therefore, is to provide a condenser discharge ignition system with surface gap spark plugs to eliminate spark plug fouling by causing the spark to occur in the immediate vicinity of the fouling deposits and be sufficiently hot to burn said deposits away.

2

A specific object is to provide a distributor rotor arm with a main spark gap and a teaser gap in parallel so as to simplify the maintenance and installation of these gaps in the ignition circuit.

5 Another specific object is to provide a distributor rotor arm with adjustable main spark and teaser gaps.

Another object is to provide an improved ignition system characterized by its ability to produce a spark of sufficient duration and heat to insure proper ignition of cold, lean and other combustion mixtures, and combustion of the fouling deposits.

Another object of the invention is to provide an improved ignition system which operates at a high frequency and low voltage compared to other systems known in the art.

15 A further object is to provide an ignition system capable of utilizing the residual energy of the ignition coil after the plug fires to maintain an arc having sufficient heat to aid in burning away fouling deposits and in igniting all fuel mixtures.

20 A still further object of the invention is to provide an improved ignition system which is characterized by its ease of operation and its relatively few number of parts.

Essentially the invention relates to an improved ignition 25 system utilizing conventional circuitry on the primary side of the ignition coil which delivers a relatively low frequency and low voltage power. The secondary circuit of the ignition coil is loaded by a secondary or ignition condenser and is electrically connected in series to a brush type distributor through the rotor arm thereof which is provided with a main spark gap and a teaser gap in parallel. The absence of rectifiers in the present system is particularly noted and the reasons therefor are described below. The distributor is connected in the conventional manner to a plurality of surface gap spark 35 plugs generally of the type disclosed in the aforementioned patent application and described below. By employing such a system the series main gap breaks down at a predetermined relatively low voltage and the charge which

40 has been built up on the secondary condenser discharges to the spark plug being fired to produce a spark of very short duration which is sufficiently hot to burn away fouling deposits. Moreover, the absence of rectifiers in the system allows the residual energy of the coil to be used to recharge the secondary condenser to a progressively diminishing degree or continue an arc across the series gap and plug for a period of time sufficient to insure complete fuel ignition. The resistor 48 helps prevent oscillatory recharging of the secondary condenser and

45 allows continuous arcing. The ionized condition of the series and spark plug gaps allows the flow of current in the secondary circuit to maintain the plug arc until the energy decays to a level which will no longer support the arc.

55 Among the more significant advantages obtained by placing the main spark gap or condenser discharge gap and the teaser gap in the rotor arm are: that a single metal distributor cap may be used to simultaneously 60 shield the adjacent portions of the electrical system from the high frequency waves emanating from the discharge gap and the teaser gap which shielding results in a considerable cost saving and also reduced gap noise; the accessibility of the rotor arm and gaps for installation, 65 replacement, repair, and adjustment of the gaps; the movement of the rotor arm resulting in air flow past the gap electrodes tending to remove shunting deposits of tungsten or other electrode metal oxides therefrom; the location of the rotor arm which inherently subjects these 70 gap electrodes to breaker point vibration tending to dislodge fouling deposits from the electrodes; and the necessary resistances for the circuit can also be placed

in the rotor arm in their proper circuit relationship with respect to the gap electrodes for simplified installation and maintenance thereof.

Other objects and advantages of the invention will become apparent from the following description and drawings, in which:

FIGURE 1 is a schematic illustration of the electrical circuitry of the invention;

FIGURE 2 is a top elevational view of the rotor arm;

FIGURE 3 is a cross sectional view of the rotor taken along line 3-3 of FIGURE 2;

FIGURE 4 is a partial sectional view of the rotor taken along line 4-4 of FIGURE 3;

FIGURE 5 is a side elevational view of a distributor;

FIGURE 6 is a cross sectional view of the distributor cap taken along the line 6-6 of FIGURE 5 in the direction of the arrows;

FIGURE 7 represents a cross sectional view of the surface gap spark plug; and

FIGURE 8 represents a side view of a variation of rotor body structure.

Referring to the drawings and in particular to FIGURE 1, an ignition system is shown comprising a direct current power source 10 such as a battery or dynamo which is connected to ground and to an ignition switch 12 of the primary circuit 13. This switch is connected through a variable ballast resistor 14 to the primary winding 16 of a transformer or ignition coil 18. A pair of breaker switches 20 and 22 are connected in parallel with a spark suppressing and primary voltage build-up condenser 24 and are grounded at 26. Switches 20 and 22 represent the equivalent of the conventional breaker point contacts of ignition systems such as are shown in the aforementioned patent and are alternately opened and closed to produce a pulsating direct current in winding 16. Condenser 24 prevents excessive sparking at switches 20 and 22 and in series with winding 16 causes a high voltage oscillation in the primary circuit.

The flux change linking both winding 16 and winding 28 and caused by the collapse of the primary current when the points 20 and 22 are opened induces an oscillatory current flow in the secondary circuit 15 comprised partially of the secondary winding 28 of coil 18 which on the first quarter wave of oscillation energized the secondary or ignition condenser 30 to a voltage of approximately 2-5 kilovolts. This condenser has one plate connected to ground and the other plate connected to said secondary winding and to a parallel arrangement of a main series spark gap 32 and a teaser spark gap 34. Teaser gap 34 is almost continuously ionized and tends to stabilize the voltage necessary to spark the main gap 32 at between 2,000 to 5,000 volts. A resistance 35 is placed in the teaser circuit to limit the current flow across this gap so as not to allow a significant discharge of the secondary condenser 30. The condenser 30 will charge up to the voltage necessary to spark series gap 32 and spark plug gap 42 which results in a high current flow in the secondary circuit to the plug.

As a result of this high current flow the arc between the concentric electrodes 44 and 46 of the surface gap plugs 42 is very hot and is maintained for a very short time of approximately one microsecond. This hot arc occurs directly across the face of the dielectric separator 45 on which the fouling deposits occur and is particularly effective in burning these fouling deposits from this face and also in igniting lean fuel mixtures.

Following the secondary condenser discharge is a low current arc maintained for approximately 250 microseconds by the residual energy of the coil 18. This residual energy is derived from continued oscillation of current in the primary circuit, while the points are opened, caused by the electrical resiliency of primary condenser 24 as it alternately attains charge and loses charge and also by the self-inductance of primary inductor winding 16. This low current arc is especially suitable for igniting certain

cold and moisture laden fuel mixtures and continues until the voltage induced by this residual energy cannot support the arc. By so utilizing this residual coil energy to supplement the energy of the condensers initial discharge the size of condenser 30 may be held to a capacitance of approximately 1000 micromicrofarads which reduces condenser cost and also reduces the degree of arc erosion of the plug electrodes.

In order to prevent overly rapid dissipation of energy through the spark plug, to help in igniting cold fuel mixtures, to aid in reducing radio interference, and to help reduce electrode arc erosion, a resistor or inductance 48 may be placed in the circuit. This resistor or inductance 48 also assists in maintaining the arc at the spark plug after the initial discharge of condenser 30.

Plug 42 is disclosed in further detail in applicant's pending application Serial No. 696,845, and comprises an outer shell or ground electrode 52 of conductive material which is swaged or otherwise formed over at the end 54 to retain the inserts 44, 46 of molybdenum or other high temperature resistant metal and the dielectric insulator 45 which may be of porcelain or other insulative material known to the art. A center or power electrode 56 is spaced from the outer shell by insulator 58 and is provided with a collar 60 which holds dielectric insert 45 in place. Powdered insulator material 62 is compressed by the action of the assembly lock nut 64 to thereby properly position and maintain the plug parts in such position. As stated above, the voltage necessary to initiate the spark in the plug gap is approximately 2,000 volts which is considerably less than that required to arc a conventional air gap spark plug.

Referring to FIGURES 3, 4, and 5, the rotor arm 66 to be used in distributor 68 is comprised of a body 70 of plastic or other electrically insulative material and is provided with a socket 72 for receiving the rotor drive shaft 74 and a cavity 76 for housing the gap structure. This cavity 76 could also be in the shape of a slot 77 across body 70 as shown in FIGURE 8 formed by removing side walls 78 of body 70 shown in FIGURE 4 to allow increased air circulation in the vicinity of the gaps to assist in removing oxide deposits therefrom. Body 70 is provided with two bores 80 and 82 which extend into cavity 76 and communicate with ledge 84 on one end of said body to form corresponding grooves 81 and 83 therein. An electrically conductive tube 86 carrying a tungsten or other high temperature resistant electrode cap 88 on one end thereof is slidably received in bore 82 and is adjustable longitudinally therein. A resistor 35 having a tungsten or other high temperature electrode cap 92 on one terminal end 93 thereof and a metal tube 94 swaged over on one end and soldered at 96 to the other terminal end 97 of said resistor is slidably received in bore 80 and is adjustable longitudinally therein. An electrically conductive clamping plate 98 is mounted on ledge 84 and contacts tube 86 and tube 94 to provide an electrical path therebetween. Power lead spring contact 100 adapted to contact the power inlet terminal 102 in the distributor cap 104 shown in FIGURE 6 is secured to plate 98 by bolt 106 and nut 108 which maintains a firm electrical connection between spring contact 100 and electrode caps 88 and 92.

An electrically conductive strip 110 is non-adjustably secured to body 70 by a bolt 111 and nut 112 and is formed into a cross bar 114 at one end which extends into cavity 76. Tungsten or other high temperature resistant electrode caps 116 and 118 are secured to cross bar 114. Tube 86 and resistor 35 may be adjusted in their bores to properly space caps 88 and 116 and 82 and 118 respectively to thereby form the main spark or condenser discharge gap 32 and the teaser gap 34. Strip 110 is formed at its other end into a brush retaining bearing or socket 120 which slidably receives a graphite-copper brush 122 which is urged in one direction by a spring 124 secured to body 70 by nut 112. Brush 122

is adapted to slidably engage the conductive segments 126 on the distributor cap 104 to complete at each contact of said segments an electrical circuit from the secondary winding 28 and condenser 30 through the spark plugs 42 which are connected through leads 128 to the segments 126. In the operation of this system, as brush 122 wipes across each of the segments 126 the condenser 30 discharges across gap 32 through the lead 128 and plug 42 connected thereto.

I claim:

1. In an operative ignition circuit for a multiple cylinder engine, a distributor having an inlet terminal and a plurality of outlet terminals, a plurality of surface gap spark plugs connected with said outlet terminals respectively, said distributor also having a rotatable arm, brush means carried by said arm and arranged to contact each of said outlet terminals successively upon rotation of said arm, spark gap means carried by said arm and requiring a predetermined comparatively high breakdown potential to initiate conduction of electric current and being thereafter susceptible of conducting at a lower conducting potential until the latter potential is subjected to a predetermined interruption, one side of said gap means being electrically connected with said inlet terminal, the other side of said gap means being electrically connected with said brush means, a storage condenser electrically connected with said inlet terminal to discharge through said plug and gap means when the latter is conducting, electrical power supply means for charging said condenser to said breakdown potential to effect a sudden current surge through said gap means and plug upon the discharge of said condenser, and resistance means for retarding the rate of discharge of said condenser sufficiently as the potential of the latter approaches said conducting potential to prevent said predetermined interruption of said conducting potential by damping

30

35

oscillation of said condenser potential, said power supply means being effective to supply electrical power to said gap means at said conducting potential for an extensive time interval with respect to the duration of said current surge to effect a trailing current of extensive duration across said gap means and plug following said current surge.

2. The combination according to claim 1 wherein said gap means includes a main gap having a fixed and an adjustable electrode mounted on said arm at opposite sides of said gap means to enable adjustment of the gap between said electrodes, said gap means also including a teaser gap having a fixed and an adjustable electrode mounted on said arm at opposite sides of said gap means in parallelism with said main gap to enable adjustment of the gap between the latter electrodes.

3. The combination according to claim 1 wherein said resistance means interconnects said condenser and inlet terminal.

20 4. The combination according to claim 3 wherein said power supply means includes a battery, a transformer having primary windings connected with said battery to be energized thereby and also having secondary windings connected with said condenser to charge the same, and 25 a condenser and breaker point in an operative oscillator circuit with said primary windings for interrupting the energizing thereof to effect a condenser charging potential across said secondary windings.
